UNITED STATES PATENT OFFICE.

CARLOS A. BLUME, OF NEW YORK, N. Y.

NECKTIE-GUIDE.

1,324,028.

Specification of Letters Patent.

Patented Dec. 9, 1919.

Application filed April 24, 1918. Serial No. 230,477.

To all whom it may concern:

Be it known that I, CARLOS A. BLUME, a citizen of Peru, residing at New York, in the county of New York, State of New York, have invented certain new and useful Improvements in Necktie-Guides; and I do hereby declare the following to be a full, clear, and exact description of the invention, such as will enable others skilled in the art 10 to which it appertains to make and use the same.

The present invention relates to new and useful improvements in means for positioning and holding portions of a person's apparel in proper relation, and is more particularly directed to the provision of a device for insuring proper sliding movement of a necktie within a turned down collar of conventional type and for preventing undesired movement of the coat collar with respect to the shirt collar, to thus prevent the coat collar from "riding up" or bulging, whereby it is maintained in proper position below the edge of the shirt collar and may 25 not contact with the neck or hair of the wearer and thus become soiled.

It is in general the object of the present invention to simplify the structure and improve the efficiency of devices of this character, more particularly with respect to the readiness with which they may be associated with the apparel of the wearer, and with respect to positive operation in the various holding functions.

More particularly, it is the object to provide a device which may be positioned within the fold of an ordinary turned down collar to provide throughout the major extent of the collar a free open channelway for receiving the necktie, to permit free sliding movement thereof in properly positioning and tying it.

It is a further object to utilize this channel forming member as a means for holding the coat collar in proper place.

With the above and other objects and advantages in view, the invention resides more particularly in the novel combination, formation and arrangement of parts herein-after described and particularly pointed out in the appended claim.

In the accompanying drawings:

Figure 1 is a perspective view of the improved device having a necktie positioned 55 therein, and itself disposed within the fold

of an ordinary turned down collar which is shown in dotted outline.

Fig. 2 is an enlarged vertical sectional view therethrough and through the shirt collar at the point of attachment of the coat 60 collar.

Fig. 3 is fragmentary bottom plan view of the guide thereof.

Fig. 4 is a fragmentary horizontal sectional view of the guide on the plane indicated by the line 4-4 of Fig. 2.

Fig. 5 is a perspective view showing a set of the coat collar holding members of the device.

Referring now more particularly to the drawings, there is shown in dotted outline a conventional turned down collar 6 with which the present device is associated. The body of the device is formed of a single plate of resilient metal bent longitudinally 70 to form a pair of spaced inner and outer side walls 7 and 8 respectively defining in conjunction with the plate portion at its bend a channelway of decidedly oblong cross section to correspond with the cross section 80 of a necktie, and open at its bottom, the plate being further transversely bent in the major arc of a circle to correspond to the general curvature of a collar, and the plate is sufficiently flexible to fit within collars of 85 various sizes, this flexibility being enhanced by series of transverse slots 9 formed continuously throughout the extent of said walls and extending from points immediately adjacent the top and bottom edges 90 thereof, whereby a substantially skeleton structure is procured, thus affording a desired lightness as well as increased flexibility. It is noted that the ends of the channelway formed by the plate terminate short 95 of the ends of the outer wall of the collar, since no pressure would occur at these portions to prevent free sliding movement of the necktie. To hold the lower edge portions of the channel walls 7 and 8 in spaced 100 relation, and yet permit ready insertion of the necktie into the channelway throughout the lower portion thereof, the lower edge portions of the plates are provided with opposed pairs of projections or knobs 10 struck 105 inwardly therefrom.

Thus a necktie may be inserted in the device in a most ready manner, in the channel member, and the member then inserted with-in the fold of a collar, which is then put 110

on in the usual manner and buttoned, and the necktie may be most readily slid in the collar, for the proper positioning and tying thereof, it being noted that the channel member also prevents the necktie from possibly working down below the collar. Although the channel member may be retained in the collar by friction, and by slight resilient pressure which might be set up therein, there is provided a more positive means in the present instance for holding the channel member in place which comprises a lug 11 depending from the central portion of the inner side 7 of the channel member and provided with an opening adapted to receive the rear collar button. As shown more particularly in Fig. 4, the end edge portions of the channel sides 7 and 8 are curved outwardly to prevent frictional engagement with the necktie. To hold the coat collar in proper relation to the shirt collar by the device when assembled in the latter, a plurality of hook members are provided. Each hook consists of a single length of wire that is bent upon itself to form a two-part bill 12, the wire at both sides of the bend being then again bent upon itself to form the double stem 13 of the hook. This double stem extends slightly beyond the point of the bill where both sides of the wire are then again bent upon themselves into parallel spaced relation to the stem 13, these last-named portions being shown at 14 and extending divergently to their free ends where they terminate in outwardly directed eyes 15. The eyes 15 provide means to receive rivets or other means for fastening the hooks to the lower edge portion of the outer channel side 8. In application, the lower edge of the outer side of the shirt collar is received within the U-shaped shank, and the bill 12 thus depends at the outer side of the lower edge portion of the collar for engagement in

the outwardly struck keeper portion 17 of a plate 18 secured to the inner side of the 45 coat collar, it being noted that inasmuch as the tendency to displacement of the coat collar is always upwardly, accidental displacement of the keeper from the hook is normally prevented, and the coat collar is 50 held in proper snug relation to the shirt collar in the various bending or other positions which would otherwise tend to cause the coat collar to "ride up" on the shirt collar in a somewhat unsightly manner and permitting soiling contact of the coat collar with the hair or neck of the wearer. 55

While I have shown and described a preferred embodiment of my invention it will be understood that the plate forming the 60 channelway may be made of metal or other material affording a desired flexibility and strength, and that various changes and modifications of structure may be resorted to without departing in any manner from the 65 scope of the invention as defined in the accompanying claim.

What is claimed is:

A device of the class described comprising a member adapted to fit within the fold 70 of a turned down collar for engagement with a necktie therein, a hook member including a U-shaped shank having the upper end of one leg secured to said member and a bill depending from the other leg of the 75 shank, said U-shaped shank being adapted to receive the outer portion of a collar and a keeper member adapted for securing to a coat collar for engagement by said bill.

In testimony whereof, I affix my signature, in the presence of two witnesses.

CARLOS A. BLUME.
